[57] **CLAIM**

The ornamental design for a battery housing for a communications transceiver, as shown.

DESCRIPTION

FIG. 1 illustrates a front view of an battery housing for a communications transceiver our new design;

FIG. 2 illustrates a right side view thereof;

FIG. 3 illustrates a left side view thereof;

FIG. 4 illustrates a top view thereof;

FIG. 5 illustrates a bottom view thereof;

FIG. 6 illustrates a back view thereof; and,

FIG. 7 illustrates a perspective view thereof.

FIG. 1

FIG. 2

FIG. 3

FIG. 4

FIG. 5

FIG. 6

FIG. 7
